CLAIM

The ornamental design for a personal emergency response device, as shown and described.

DESCRIPTION

FIG. 1 is a front perspective view of a personal emergency response device with clip showing my/our new design;
FIG. 2 is a back perspective view thereof;
FIG. 3 is a front elevation view thereof;
FIG. 4 is a left side elevation view thereof;
FIG. 5 is a right side elevation view thereof;
FIG. 6 is a back elevation view thereof;
FIG. 7 is a top plan view thereof; and,
FIG. 8 is a bottom plan view thereof.

The broken lines depict unclaimed environmental subject matter.
